UNITED STATES PATENT OFFICE

2,110,401

BEAD RUNNER

Marshall F. Prangley, Transvaal, Union of South Africa

Application March 25, 1937, Serial No. 133,056

1 Claim. (Cl. 72—131)

My invention relates generally to means for moulding and finishing beads on plaster walls and the like plastic material objects, and particularly to a bead runner for moulding and finishing a bead on a plaster wall, and an important object of my invention is to provide means of the character indicated which enables the production and finishing of beads with large savings in time and materials.

10 Other important objects of my invention will be apparent from a reading of the following description in connection with the drawing, wherein for purposes of illustration I have shown preferred embodiments of my invention.

15 In the drawing:—

Figure 1 is an elevational view of the lower part of a plaster wall showing an embodiment of the invention in operative relation thereto and in process of moulding and finishing a bead on the

20 wall.

Figure 2 is a bottom plan view of the bead runner.

Figure 3 is a transverse vertical sectional view taken through Figure 2 approximately on the line 3—3.

25 Figures 4 and 5 are views similar to Figure 3 of runners with modified bead forming elements.

Referring in detail to the drawing, the numeral 5 generally designates the bead runner which is 30 conveniently in the form of a flat block 6 provided with a U-shaped handle 7 whose legs are attached to or integral with the opposite ends of the block at the longitudinal center thereof and immediately over the wedge-shaped longitudinal

35 groove 8 which is formed in the flat plain bottom 9 of the block 6, and in which is set the bead forming element 10 which is shaped on its underside with a groove formation 11 which may be varied to give desired contours to the bead 12 on the wall 13.

40 The embodiments of my invention shown in Figures 4 and 5 are similar in all respects to the embodiment shown in Figure 3 except that the bead forming elements 10a and 10b thereof have 45 different groove forming contours 11a and 11b, respectively.

In operating the device of the invention for purposes of producing the finished bead 12, the

wall is plastered and a groove is left in the plaster at the required height from the floor. A running rule 14 is then nailed as indicated by the numeral 15 to the wall at the bottom of the groove 16, and on this rule the device 5 is manually moved 5 so as to form and finish by moulding and pressure and friction a filling composed preferably of fine sand, cement, and plaster of Paris. After the filling has been placed in the groove the tool is applied to the running rule and run along the 10 full length of the bead to be constructed. It is only necessary to pass the tool three times along the work usually to produce a finished bead, and to produce a bead which has fine clear cut top and bottom boundaries.

15 In the case of the embodiment of the invention shown in Figure 4, the effect of a double bead is available whereas the embodiment of the invention shown in Figure 3 produces a single broad bead. The embodiment of the invention shown 20 in Figure 5 makes available a concave bead with outstanding borders. Any desirable contour of bead may be provided for by correspondingly shaping the bead forming element.

25 Although I have shown and described herein preferred embodiments of my invention, it is to be definitely understood that I do not desire to limit the application of the invention thereto, and any change or changes may be made in the materials, and in the structure and arrangement of the parts, within the spirit of the invention and the scope of the subjoined claim.

What is claimed is:—

A bead forming tool of the class described comprising a rectangular shaped block, a handle 35 connected to one face thereof, the other face being flat and the flat face having a groove in its central portion extending from one end of the block to the other end, the groove being of dovetail shape in cross section and a bead forming 40 member having a dovetail shaped part slidably arranged in the groove, with the bead forming portion projecting from the said face of the block and the side edges of the block being straight and spaced considerable distances from 45 the bead forming member.

MARSHALL F. PRANGLEY.
